UNITED STATES PATENT OFFICE.

WILLIAM S. WELLS, OF SOUTH BETHLEHEM, PENNSYLVANIA, ASSIGNOR TO BENJAMIN EASTWOOD COMPANY, OF PATERSON, NEW JERSEY, A CORPORATION OF NEW JERSEY.

WEFT STOP MOTION FOR LOOMS.

Application filed November 11, 1922. Serial No. 600,263.

To all whom it may concern:

Be it known that I, WILLIAM S. WELLS, a citizen of the United States, residing at South Bethlehem, in the county of Lehigh and 5 State of Pennsylvania, have invented certain new and useful Improvements in Weft Stop Motions for Looms, of which the following is a specification.

This invention relates to weft stop motion mechanisms for looms and it consists in certain improvements, first, in the means on the batten which detects the absence of weft or filling and thereupon transmits the motion of the batten to movable means which 10 shifts the loom controller to position for stopping the loom and, second, in the said means which shifts the loom controller to the stopping position, the principal objects being to provide a weft-stop motion mechanism which may be used as a "center" stop motion mechanism, and as such shall be adapted to be inoperative to cause stopping of the loom for the first pick following absence of filling and consequent stopping 15 20 25 (that is, until the shuttle on its second shot following starting up can have laid the filling in operative relation to the detecting means, under its weft-fork), and which, further, shall permit a loom to be driven at higher speed than is possible with previous mechanisms of this class and yet perform its functions reliably.

Fig. 1 is a fragmentary front elevation of a loom embodying my invention, the breast beam and parts thereon being broken away to show certain other parts more clearly;

Fig. 2 is a view on a larger scale showing the breast-beam and batten and the improved mechanism in plan;

Fig. 3 shows the breast-beam and batten in section and my mechanism in side elevation with the parts thereof in the positions they occupy when the batten is back;

Figs. 4, 5 and 6 are similar views but respectively showing said mechanism with the parts thereof positioned as follows, to wit, when the loom is about to be stopped on absence of filling; when the loom has been stopped, the batten having gone back; and when the loom has been again started and the batten is performing its first forward movement thereafter;

Fig. 7 is a plan of the batten and that portion of the mechanism which is mounted 55 thereon;

Fig. 8 is a sectional view on line 8-8, Fig. 7;

Fig. 9 is a plan, partly in section, of a certain weft-fork-forming member and the 60 means for effecting adjustment thereof; and

Figs. 10 and 11 are detail views of the weft-fork.

Let *a* and *b* represent the knock-off shaft and handles therefor of the loom, said shaft being suitably journaled in the sides of the loom frame *A* in the usual way. The structure *a b* I herein term the controller of the loom and to that end it may be assumed, for example (suitable means, not shown, being provided for driving the loom and incidentally reciprocating the batten toward and from the breast-beam), that said lever controls braking means for the loom (as in the Zeedyk Patent No. 1,360,487), the brake being released when the controller stands as in Figs. 3, 4 and 6 but applied when the controller stands as in Fig. 5.

c is the breast-beam and *d* is the batten.

A bracket *e* is secured to the front face of the batten, the same being channeled at the front and having its upper portion slotted as at *e'* (Fig. 2), for the play up and down in its slot of a weft-fork *f* pivoted in the bracket and having a hook *f'* 85 projecting forwardly and downwardly.

The weft-fork also has projecting downwardly therefrom a stud *f*² to which is connected one end of a spiral spring *g* which tends to hold the weft-fork normally depressed, being for that purpose attached to the crank *h'* on one end of a rod *h* which at its other end has a crank *h*² for rotatively adjusting it in its bearings *i* and *j*, the former of which is a screw axially bored

90 to receive the rod and is tapped into one side of the bracket *e* and the latter of which is a clip attached to the batten and having a screw *j'* to cause it to clamp the rod and hold it where rotatively adjusted; adjustment rotatively of the rod, whose crank or handle projects clear of the fabric being woven, obviously varies the tension of the spring and consequently the pressure of the weft-fork on the weft or filling *B* against 105 which the weft-fork presses at the recess *k*.

(Fig. 2) in the batten. In bearings at the lower end of the bracket *e* is journaled the shaft *l* of a dagger or dagger structure which includes the dagger proper *n*, secured 5 on said shaft by the set-screw *n'*, a catch-arm *m*, set fast in a transverse hole in the shaft and having its free end bent off as at *m'* (Figs. 7 and 8) and a split wiper-arm *o* clamped on the shaft by a set-screw 10 *o'* and having a rounded under surface *o''*. The dagger and weft-fork coact reciprocally thus: Each time the former swings up, or counter-clockwise, the end *m'* of its catch-arm bears against the shank of the hook *f'* 15 and elevates the weft-fork; when it swings down it allows the weft-fork to drop and, if there is failure of filling and the weft-fork can thus enter slot *k*, the hook-proper *f''* on hook *f'* will engage end *m'* of the catch-arm 20 (since they move in intersecting arcs shown dotted in Fig. 4) and stop the movement of the bell-crank lever, which otherwise continues moving to a further limit. Means is 25 provided for causing upward movement of the dagger, when the batten recedes and the weft-fork is to rise to permit the shuttle to pass, and its downward movement, when the batten moves forward and the weft-fork is to "feel" for the filling, as follows: The latter movement is caused by a spring *p* interposed between the butt of the dagger proper 30 and the bracket *e*; gravity of course is also a factor in this, so I do not wish to be limited to the use of means, such as this spring. 35 The former or upward movement is caused by the wiping of a roller *q* against the rounded under surface *o''* of the wiper-arm *o*, the roller being carried by a lever *r* pivoted in bracket *e* on a stud *s* and having its 40 free end pivotally connected to a link *t* which is in turn connected (preferably by being pivoted to a stud *u*) with some fixed part, as the bracket *v* secured to the under side of the breast beam and incidentally forming a 45 center bearing for the knock-off shaft; forward and backward adjustment of the stud *u* is possible by arranging it in a slot *w* in said bracket.

On the knock-off shaft a collar *x* is secured by a set screw *y*, the same having a depending web *z*. On the pin 2 in this web is fulcrumed a toggle lever 3 which has a spring 4 connecting it at one side of its fulcrum with a pin 5 on the web at the opposite side of its fulcrum, said lever being 55 movable between limits determined by the stops 6 and 7 in such manner that when it bears against one or the other stop the point at which the spring is connected to the lever 60 will be at one side or the other of a straight line passing through the points 2 and 5. The end of the lever adjoining the batten has a notch 8 to receive the impact of the end of the dagger; if (the lever being in the 65 position shown in Fig. 4) it is impinged by

the dagger and so causes the controller to rock from the position shown in Fig. 4 to that shown in Fig. 5, the other end of the lever will be brought against a spring secured in bracket *v* and thus shifted from 70 contact with stop 7 to contact with stop 6, clearing the dagger. The latter end of the lever 3 has an underneath cam face 10 adapted to be impinged by the dagger. The web is formed with a camming shield 11 present 75 only to fend the dagger downwardly if, through improper adjustment or some other fault, its free end should in its knocking-off thrust stand too high.

Operation.—The reciprocal coaction of the weft-fork and dagger has been already explained. If there is failure of filling or weft, on the ensuing forward movement of the batten the dagger will be checked in its downward or clockwise movement by the weft-fork hook *f'* and, being held in the position of Fig. 4, will impinge against the notched end of lever 3 and through the latter rock the controller to the position of Fig. 5, the lever being shifted by spring 9 clear 90 of the dagger or to idle position. The loom will thus be stopped, the batten coming to a standstill at about the position shown in Fig. 5. When, upon shifting the controller to the position of Fig. 6, the loom is again started, 95 since there is still (on the first forward movement of the batten) failure of filling, the dagger will be again caught and held by the weft-fork hook *f'* in the position shown in Fig. 4; but, since lever 3 is still in the idle 100 position, the dagger will clear its notched end and so not effect a second shifting of the controller (Fig. 6) but it will, however, engage its cam face 10 and so rock it back to active position, ready to act to cause shifting 105 of the controller on failure of filling on the next or any succeeding forward movement of the batten.

When the weft-fork in descending about reaches the feeling position the stroke is 110 normally (i. e., if filling is present) continued without the dagger having any further influence on the weft-fork. Thus, since the mass represented by the dagger 115 (and necessary for the latter to perform its work of knocking-off) is not a factor to be considered in determining and applying to the weft-fork the force which is required to effect the feeling, it is possible to use a very light spring, as *g*, to afford this force; previous constructions, on account of the dagger continuing to influence the weft-fork in the acutal feeling part of its stroke, required springs strong enough to control the dagger's mass and it was practically impossible (especially in high speed looms) to obtain such nice adjustments that the weft-fork would not either fail to detect or would detect prematurely and cause what is known as "looping" of the filling. Again, since in 120 125 130

the descent of the weft-fork and dagger the latter either is caught and held by the former positively at a given elevation or allowed to proceed on to a lower one entirely independently of any further movement of the weft-fork, it is possible to construct the parts so that the dagger will always strike a clean square blow in knocking-off, or clear completely, and the mechanism is prevented from becoming unreliable in action as the result of the marring of the impact faces that glancing blows produce.

The spring g acts on an eccentric point (in arm f^2) of the weft-fork to turn it on its axis to a definite position, and when it is in this position it is in or approximately in the feeling portion of its range of movement, or that part of its downward movement where it is about to enter recess k . The force represented by the spring is therefore desirably less in the feeling part of the stroke than when the weft-fork is raised, when the spring should insure the descent of the weft-fork, when that occurs, as fast as the descending dagger will permit. The dagger is made to rise at a speed which is gradually accelerated and fall at a speed which is gradually retarded (which involves smoothness and reliability in the action of the parts) by forming the surface o^2 in a suitable cam-like curve; but at the end of the wiper-arm this curve becomes the arc of a circle of such radius that when the roller q rolls in contact with this part of the surface (which is when the dagger and hence the weft-fork are fully up) the weft-fork stands at dwell thus to afford time for the shuttle to pass.

The device h forms a simple and convenient means for adjusting the pressure of a weft-fork on the filling or weft, whether the weft-fork is acting, as here, as a detector in a stop-motion mechanism or otherwise.

Having thus fully described my invention, what I claim as new and desire to secure by Letters Patent is:—

1. In combination, with the fixed structure of a loom and a batten-including structure movable in the fixed structure back and forth, a weft-detecting device pivotally movable on the second structure into and out of and normally urged into position to detect failure of weft on said second structure, a dagger pivotally movable on said second structure in one direction against said device to move it out of said position but normally urged in the opposite direction, said device and dagger having their axes of movement parallel, means to press the dagger against said device on each back and forth stroke of the second structure, said device having means to check movement of the dagger in said opposite direction on failure of weft and consequent movement

of said device into said position, and a shiftable loom-controller-including means arranged to be shifted by the dagger.

2. In combination, with the fixed structure of a loom and a batten-including structure movable in the fixed structure back and forth, a weft detecting device pivotally movable on the second structure into and out of position to detect failure of weft on said second structure, a spring yieldingly holding said device in said position, a dagger pivotally movable on said second structure in one direction against said device to move it out of said position but normally urged in the opposite direction, said device and dagger having their axes of movement parallel, means to press the dagger against said device on each back and forth stroke of the second structure, said device having means to check movement of the dagger in said opposite direction on failure of weft and consequent movement of said device into said position, and a shiftable loom-controller-including means arranged to be shifted by the dagger.

3. In combination, with the fixed structure of a loom and a batten-including structure movable in the fixed structure back and forth, a weft-detecting device movable on the second structure into and out of and normally urged into position to detect failure of weft on said second structure, a dagger pivotally movable on said second structure in one direction against said device to move it out of said position but normally urged in the opposite direction, means including a lever to press the dagger against said device on each back and forth stroke of the second structure, said lever and dagger having their axes of movement parallel and one having a cam to wipe against the other and said device having means to check movement of the dagger in said opposite direction on failure of weft and consequent movement of said device into said position, and a shiftable loom-controller-including means arranged to be shifted by the dagger.

4. In combination, with the fixed part and the back-and-forth movable batten-including structure of a loom, a weft-stop motion mechanism including a loom-controller-including means shiftable in said fixed part of the loom, a dagger member pivotally movable on said structure into and out of position to engage and shift said means, and a weft-detecting device movable in said structure by the dagger out of detecting relation to the weft and normally urged into said relation and controlling the movement of the dagger to its said position, said mechanism also including a lever member for moving the dagger member out of said position fulcrumed in said structure on an axis parallel with the axis of movement of the dagger and operatively connected with

the fixed part of the loom to be moved thereby and one of said members having a camming engagement with the other.

5. In combination, with the fixed structure of a loom and a batten-including structure movable in the fixed structure back and forth, a web detecting device pivotally movable on the second structure into and out of position to detect failure of weft on said second structure, means, including a pivoted dagger and movable back and forth on said second structure, for moving said device into and out of said position, said device and dagger having their axes of movement parallel and said device having means on failure of filling to maintain the dagger at standstill in and relatively to said second structure, and a shiftable loom-controller-including means arranged to be shifted by the dagger when the latter is at such standstill.
6. In combination, with the fixed structure of a loom and a batten-including structure movable in the fixed structure back and forth, back and forth shiftable controller-including means on the first structure, said means having a stop, a lever movable on said means back and forth from and to and normally abutting the stop, weft-controlled means on the second structure having a dagger movable to a definite position in the second structure and thereupon adapted to engage a part of said lever and through the lever shift the first means, and means arranged in the path of movement of the lever

with the first means on shifting of the latter, 35 to move the lever clear of the dagger.

7. In combination, with the fixed structure of a loom and a batten-including structure movable in the fixed structure back and forth, back and forth shiftable controller-including means on the first structure, said means having a stop, a lever movable on said means back and forth from and to and normally abutting the stop, weft-controlled means on the second structure having a dagger movable to a definite position on the second structure and thereupon adapted to engage a part of said lever and through the lever shift the first means, and means on such shifting of the first means to move the 50 lever clear of the dagger, said lever on shifting of the first means back again having another part thereof projecting into the path of movement of said dagger when in said position and the lever being thereby 55 adapted to be returned by the dagger into contact with said stop.

8. In combination, with supporting means on which the weft is laid, a pivoted weft-fork movable toward and from the weft laid 60 on said means, a spring connected to an eccentric point of the weft-fork, and an adjusting member for the spring rotatively adjustable in said means and having the spring connected to an eccentric point thereof.

In testimony whereof I affix my signature.

WILLIAM S. WELLS.
